UNITED STATES PATENT OFFICE.

JAMES C. BENNETT, OF NEW YORK, N. Y., ASSIGNOR OF FORTY PER CENT TO WILLIAM H. FRASER, OF NEW YORK, N. Y.; FIVE PER CENT TO GONZALO O'NEILL, OF EAST ORANGE, NEW JERSEY; AND FIVE PER CENT TO ARTHUR A. DE BONNEVILLE, OF BAYONNE, NEW JERSEY.

COMBINED PROPELLER AND ROTOR.

Application filed September 7, 1926. Serial No. 133,972.

This invention relates to combined propellers and rotors.

The object of the invention is the production of a rotor that is turned by streams of air, that have functioned with the blades of a propeller, and which function with a second propeller as they are discharged from the rotor, whereby the air compressed by the first propeller is used expansively in the 10 rotor and again expansively in the second propeller. The second object of the invention is the production of a pair of combined propellers and rotors that are operated by air discharged to the rear of a main 15 propeller.

The third object of the invention is the production of a pair of combined propellers and rotors, that function with the main propeller of an aeroplane to turn the shaft 20 of said main propeller. The fourth object of the invention is the production of a pair of combined propellers and rotor, that function as stabilizers for an aeroplane.

In the accompanying drawings Fig. 1 represents a top plan view of a fragmentary portion of an aeroplane with a plan view of an exemplification of the combined propeller and rotor; Fig. 2 shows a section of Fig. 1 on the line 2, 2 and Fig. 3 indicates 30 a section of Fig. 1 on the line 3, 3.

An aeroplane is indicated with the fuselage 20 having the usual opening 21 in its crown. The main propeller is indicated at 22, the engine at 23 having the shaft 24. 35 The top and bottom wings are respectively indicated at 28 and 29.

Between the wings 28 and 29 are located the similar cylindrical sleeve casings 30 and 31. Each of said casings has formed therewith the conical shaped inlet duct 32 and the conical shaped outlet duct 33. A pair of straps 38, preferably of metal, bear on the top face of the top wing 28, and each has formed therewith the bent up ends 39. 40 Similar straps 40 bear against the lower face of the wing 28, and have formed therewith the bent up ends 41 which bear on the inlet duct 32 and the outlet duct 33. Rivets 42 connect said ducts 33 and the said ends 39 and 41. A pair of straps 46 similar to 38 bear on the top face of the bottom wing 29, and each has formed therewith the bent up 45

ends 47 and 48, which bear against the ducts 32 and 33. A pair of straps 49 bear against the bottom face of the bottom wing 29 and each is indicated with bent ends 50 and 51. Rivets 52 connect the ends of the latter pair of straps to the straps 46 and the ducts 32 and 33. A strap 55 has its ends connected to the straps 38 and a strap 56 has its ends connected to the straps 49. Screws 58 extend through the strap 55 and engage frames (not shown) in the top wing 28 and screws 59 extend through the strap 56 and engage frames (not shown) in the bottom wing 29. 55 60 65

Within each of the sleeve casings 30 and 31 is located a rotor. The said rotors comprise the similar sleeves 63 and 64. Within each of the sleeves 63 and 64 is shown the barrel 65. A plurality of right handed helical blades 66 are located between and connected to the sleeve 63 and its barrel 65, and a plurality of left handed helical blades 67 are connected to the sleeve 64 and its barrel 65. 70 75

A shaft 72 is located in the axial center of each of the sleeves 63 and 64. A pair of discs 73 are fastened to each shaft 72 and support the barrels 65.

A front propeller 74 and a rear propeller 75 are fastened to each shaft 72.

A rear supporting frame comprises the top angle irons 80, 81 which extend through the fuselage 20. A bottom angle iron 82 bears up against the bottom of the fuselage 85 vertically below the angle iron 81. The vertical angle irons 83 connect the angle irons 81 and 82, and struts 84 extend between the angle irons 81 and 83. Angle irons 85 connect the angle irons 80 and 81. 90

A front supporting frame similar to the rear supporting frame is indicated with the top angle irons 90, 91 similar to 80 and 81. A bottom angle iron, not shown, similar to 82 is located vertically below the angle iron 91. Vertical angle irons 93 similar to 83 and struts not shown similar to 84 are provided. Angle irons 95 similar to 85 connect the angle irons 90 and 91. 95

Upon each of the angle irons 81 and 91 are fastened the similar journal boxes 100 in which are journaled the shafts 72. A tight pulley 101 and a loose pulley 102 are provided for one of the shafts 72 and a

tight pulley 103 and loose pulley 104 are provided for the other shaft 72.

A platform 105 is secured in the fuselage and supports the similar journal brackets 106, and 107 and 108. A shaft 109 is journaled in the journal brackets 106 and 107. A pulley 110 is fastened to the shaft 109 between the journal brackets 106 and 107. A straight belt 112 is provided for the pulleys 101, 102 and 110 and a cross belt 113 is provided for the pulleys 110, 103 and 104. A belt shifter 115 is provided for the belt 112 and a belt shifter 116 is provided for the belt 113. An electric generator 120 is supported upon the platform 105 and one end of its armature shaft 121 is journaled in the journal bearings 108. One member 122 of a friction clutch is slidably connected to the armature shaft 121, and the second member 123 of the said clutch is connected to the shaft 109 in the usual way. A journal bracket 125 supports one end of the shaft 24 and the latter has fastened thereto the spur gear 126. An electric motor 128 is supported in the fuselage and on its armature shaft 129 is rotatively supported one member 130 of a friction clutch. A spur gear 131 is fastened to the member 130. The second member 132 of the friction clutch is slidably supported on the armature shaft 129. A journal bracket 133 supports one end of the armature shaft 129.

An electric storage battery 135 is supported in the fuselage. A wire 140 with the fuse 141 connects the storage battery and the electric generator 120. An electric switch 142 is provided for the wire 140. A wire 143 with the fuse 146 connects the battery 135 and the electric motor 128. An electric switch 149 is provided for the wire 143. A wire 150 connects the electric generator 120 and the electric motor 128.

In the present exemplification of the invention with the aeroplane, when the main propeller 22 thereof is started by the engine 23, the aeroplane rises in the usual manner and the air discharged to the rear of the blades of the main propeller impinges against the blades of the propellers 74 which causes the latter to turn. The streams of air discharged to the rear of the blades of the propellers 74 enter the inlet ducts 32 and engage the helical blades 66 and 67 of the rotors. Streams of air are discharged from the blades 66 and 67 and impinge against the blades of the propellers 75. By this means the rotors with their shafts turn in opposite directions and function as stabilizers for the aeroplane. The rotations of the shafts 72 through the belts 112 and 113 are transmitted to the shaft 109, and from the latter to the armature shaft 121, by virtue of which the electric generator 120 is turned. By this means the storage battery 135 is charged. The belt shifters 115 and 116 en-

able the shaft 109 to be started or stopped at the will of the operator. Also by means of the friction clutch having the members 122 and 123, the electric generator 120 may be started or stopped. The electric current furnished by the wire 143 turns the electric motor 128. The rotations of the armature shaft 129 of the said motor are transmitted to the shaft 24 by means of the gears 126 and 131. The rotations of the two rotors with their propellers, assist the main shaft 24 in turning in addition to the rotation imparted to the shaft 24 by the engine 23.

Various modifications may be made in the invention and the present exemplification is to be taken as illustrative and not limitative thereof.

Having described my invention what I desire to secure by Letters Patent and claim is:

1. The combination of a sleeve casing, an inlet duct extending from one end of the casing, an outlet duct extending from the other end of the casing, a rotor in the casing and coaxial therewith, means to direct streams of compressed air to the said inlet duct, the air rotating the rotor and expanding, and means to again expand the air when discharged from the outlet duct.

2. The combination of a sleeve casing, an inlet duct extending from one end of said casing, an outlet duct extending from the other end of the casing, a shaft coaxial with the sleeve casing, a rotor supported on said shaft, a propeller fastened to the shaft at one end of said casing adjacent to its inlet duct and a second propeller fastened to the shaft adjacent to its outlet duct.

3. The combination of a rotor comprising a sleeve casing, an inlet duct extending from one end of the sleeve casing, an outlet duct extending from the other end of the sleeve casing, a shaft coaxial with the sleeve casing, a sleeve within and coaxial with the sleeve casing, a plurality of helical blades interposed between said sleeve and the shaft, a propeller fastened to the shaft at one end of the sleeve casing adjacent to said inlet duct and a propeller fastened to said shaft adjacent to said outlet duct.

4. The combination of a rotor comprising a sleeve, a shaft coaxial with the sleeve, a pair of discs fastened to the shaft, a barrel fastened to the discs and a plurality of helical blades interposed between the sleeve and the barrel, the outer circumferential portion of each helical blade fastened to the sleeve and the inner circumferential portion of each blade fastened to the barrel.

5. The combination of a rotor comprising a cylindrical sleeve casing, a shaft coaxial with the sleeve casing, a sleeve within the casing, a barrel within the sleeve, connecting means between the barrel and the shaft, a plurality of helical blades with their outer

portions fastened to the sleeve and their inner portions fastened to the barrel and propellers fastened to the shaft at the opposite ends of the sleeve casing.

5 6. In combination, an aeroplane, a fuselage for the aeroplane, an engine having a main shaft in the fuselage, a pair of wings for the aeroplane, a pair of rotors between the wings of the aeroplane on opposite sides 10 of the fuselage, each of said rotors comprising a sleeve casing, means to connect said sleeve casings to said wings, a shaft coaxial with each sleeve casing, a sleeve within each sleeve casing, a barrel within each sleeve, a 15 shaft within each barrel, connecting means between each barrel and its shaft, a plurality of helical blades interposed between each sleeve and its coaxial barrel and means to connect the shaft of each rotor with the 20 main shaft of the aeroplane.

7. In combination an aeroplane, a fuselage for the aeroplane, an engine having a main shaft in the fuselage, a propeller connected to said main shaft, a pair of wings 25 for the aeroplane, a pair of rotors between the wings of the aeroplane on opposite sides of the fuselage, a sleeve casing for each rotor, means to connect the sleeve casings to

said wings, a shaft coaxial with each sleeve casing, right handed helical blades turning with the shaft of one rotor and left handed helical blades turning with the shaft of the other rotor and means to connect the shaft of each rotor and the main shaft of the aeroplane.

8. In combination an aeroplane, a fuselage for the aeroplane, an engine having a main shaft in the fuselage, a propeller connected to said main shaft, a pair of wings for the aeroplane, a pair of rotors between the wings on opposite sides of the fuselage, a shaft for each rotor, an electric generator in the fuselage, adjustable means connecting the shafts of the rotors and the armatures 40 shaft of the electric generator, a storage battery in the fuselage, electric connections between the storage battery and the electric generator, an electric motor in the fuselage, electric connections between the motor and battery and adjustable connections between 45 the motor and the main shaft of the engine in the aeroplane.

In testimony whereof I affix my signature.

JAMES C. BENNETT.
